TROLLEY FOR REVOLVING DOORS

Thurloe M. Hagenbook, Evansville, Ind., assignor
to International Door Company, Evansville,
Ind., a corporation of Illinois

Application August 8, 1935, Serial No. 35,395

19 Claims. (Cl. 20—18)

My invention relates broadly to revolving doors and more particularly to a construction of trolley for supporting a revolving door with respect to the drum of the door.

- 5 One of the objects of my invention is to provide a simplified construction of trolley for revolving doors which comprises a relatively small number of parts and is relatively inexpensive in manufacture and assembly.
- 10 Another object of my invention is to provide a construction of trolley which may be readily shifted from a central position supporting the revolving door to a retracted position, in which the doors are collapsed adjacent one side of the
- 15 drum of the revolving door.

Still another object of my invention is to provide a construction of trolley wherein the upper end of the shaft of the revolving door may be readily aligned with the trolley support and

20 maintained in a position for precision operation. A further object of my invention is to provide a construction of trolley having means for positively locking the trolley in a predetermined central position for journaling the revolving door with respect to the drum of the door while permitting the unlocking thereof when it is desired to shift the collapsed door to one side of the drum.

25 A still further object of my invention is to provide a construction of gravity actuated locking means for the trolley of a revolving door for insuring the maintenance of the trolley in a position central of the drum, while permitting the unlatching of the gravity actuated lock when it is desired to collapse the door and shift the door to one side of the drum.

Another object of my invention is to provide a construction of trolley having means for compensating for differences and inaccuracies in shaft angularity or movement which may exist in various installations in order to provide a product which will meet building requirements generally.

Other and further objects of my invention 45 reside in the construction of thrust bar for journaling the shaft of the revolving door and the automatic locking means for positioning the trolley as will be set forth more fully in the specification hereinafter following by reference to the 50 accompanying drawings, in which:

Figure 1 is a sectional view of a revolving door provided with my improved trolley support; Fig. 2 is a side elevation on an enlarged scale with parts broken away and in section; Fig. 3 is a central vertical longitudinal sectional view taken on line 3—3 of Fig. 4; Fig. 4 is a horizontal sectional view taken on line 4—4 of Fig. 3; Fig. 5 is a transverse vertical section taken on line 5—5 of Fig. 3; Fig. 6 is a side elevation of one of the 55 adjustable trolley retaining lugs; Fig. 7 is a bottom

view thereof; Fig. 8 is an end elevation thereof; Fig. 9 is a detailed front elevation of the gravity actuated locking bar; Fig. 10 is a top plan view thereof; Fig. 11 is a top plan view of the housing for the trolley support; and Fig. 12 is a vertical longitudinal section thereof taken on line 12—12 of Fig. 11.

My invention is directed to a simplified construction of trolley for revolving doors which is simple in construction and comprises a small number of parts capable of inexpensive manufacture and assembly on a quantity production basis. I provide a carrier which is supported on roller members which engage parallel extending shoulders constituting rails formed on a laterally extending member projecting diametrically above the drum of the door. The carrier supports a thrust bar in which the upper end of the rotating shaft of the revolving door is journaled. The upper end of the shaft of the revolving door is mounted in a ring assembly capable of angular displacement in either of two horizontal planes to automatically compensate for inaccuracies which may be encountered in different revolving door installations. I provide special means for limiting the movement of the carrier to a position centrally of the drum of the revolving door. Gravity actuated locking means which I provide for maintaining the carrier in a position centrally of the door is a particular feature of my invention.

A horizontally extending weighted bar projects on opposite sides of the carrier and is adapted to have its depending ends latched in grooves adjacent cam faces on members adapted to be 35 adjustably secured to the diametrically extending members from which the guide rails are formed. The weighted bar is pivotally mounted with respect to the carrier and in such position that the weighted bar may be readily elevated 40 from a latched position employing a suitable tool, rod, or stick which is projected through the hollow central shaft of the revolving door. After the weighted bar is unlatched from the latching means by the simple raising operation the trolley may be readily rolled to one side of the drum with the wings of the revolving door in collapsed position. When the revolving door is returned to assembled position the trolley is readily locked in the central position for the reason that the 45 ends of the weighted bar ride up on the cam shaped faces of the locking means and latch in the adjacent notches thereof.

Referring to the drawings in detail reference character 1 designates an assembled revolving 55 door structure operating within a drum having a base 2 and a ceiling structure 3. The rotating shaft of the revolving door is indicated at 4 journaled in bearing 5 in the base 2 and journaled in the trolley structure which I have designated 60

generally at 6 mounted above the ceiling 3. I provide a diametrically extending structural member 7 mounted above the ceiling 3 of the drum. The structural member 7 is provided with 5 a central slot 8 aligned with a corresponding slot 9 in the ceiling 3, and through which the shaft 4 is adapted to be moved when the revolving door is being shifted from the central assembled position to a collapsed position in which the wings 10 are folded adjacent one side of the drum.

The structural member 7 is shaped to provide parallel extending shoulders 10 which are engaged by sets of roller members 11 and 12. I provide a carrier constituting the body structure 15 of the trolley as indicated at 14 having upwardly projecting side walls 15 interconnected by laterally extending end braces 16. The carrier is apertured through the side walls 15 thereof as indicated at 15a and 15b for the passage of rod members 17 and 18 which carry the roller members 11 and 12 respectively. The carrier 14 is provided with a central aperture 19 in the bottom thereof, through which a sleeve 20 projects upwardly as shown more particularly in Figs. 3 and 5. The 25 sleeve 20 provides an annular inner wall for the bearing structure. The outer annular wall of the bearing structure is shown at 21 secured to the bottom of the carrier and extending upwardly as shown. I provide a pair of annular plate 30 members 22 and 23 disposed between the upwardly extending housing members 20 and 21, and intermediate the plate members 22 and 23 I provide a lubricating packing ring 24 which may retain lubricating oil for continuous lubricated 35 operation of the revolving door over extended periods of time.

I have illustrated the arrangement of the annular members 22 and 23 separated by the lubricating packing ring 24 merely as one possible arrangement of the bearing structure. I may employ, if desirable, a ball or roller bearing structure for carrying the thrust effective under the weight of the revolving door. The construction which I have selected for the purpose of illustrating an 40 annular member 25 has a downwardly projecting portion which directly enters the space between the cylindrical members 20 and 21 and directly bears upon the annular member 23. The annular member 25 has a pair of upwardly projecting 45 lugs 26 which have diametrically aligned elongated recesses 27 therein. The recesses 27 are elongated to allow a sufficient amount of lost motion to permit inaccuracies which may be encountered in various constructions of revolving doors to be compensated. The recesses 27 are closed by means of strip members 27a which are secured in position by means of bolts 27b which engage the upper end of the lugs 26. The elongated recesses 27 provide means into which the 50 radially extending pins 28 carried by the annular member 29 extend. The annular member 29 is angularly displaceable within narrow limits by reason of the rocking of ring 29 on pins 28 which are free to shift in recesses 27 in lugs 26.

To further increase the adaptability of the mounting means for the rotary shaft 4 to meet various installation conditions I provide a coacting annular member 30 having recesses 30a disposed diametrically therein to receive pins 31 extending inwardly from annular member 29, but displaced 90° from the position of pin members 28. There is sufficient freedom of movement between annular members 29 and 30 to compensate for differences in various door installations which 75 may be encountered. It will be observed that the

pivotal connection of ring members 29 and 30 at a 90° displacement with respect to each other insures adjustment in two directions. That is to say, movement of rotary shaft 4 in any angular position will be compensated for by the pivotal relationship of ring members 29 and 30 for all practical purposes. It will be noted that the members 25, 29 and 30 substantially comprise a universal joint coupling especially adapted to the structure of a revolving door. In lieu thereof, I 10 may provide various forms of flexible couplings to accomplish the same purposes.

The shaft 4 is internally recessed and screw threaded in the upper end thereof as indicated at 32. A portion of the shaft indicated at 33 is reduced in cross section and screw threaded at its lower end as indicated at 34 to engage with the screw threaded recess 32 in shaft 4. The shaft section 33 is secured to the rotatable shaft 4 by means of set screw 35. The upper end of shaft section 33 is screw-threaded as indicated at 36 and is grooved at 37 to receive a lock pin 38 which also extends into aligned groove 30b, in annular member 30 and groove 39b in nut 39. The nut 39 engages the screw-threaded portion 36 of shaft 25 33 and supports the rotatable door in proper relation to the annular member 30. The supporting forces are transmitted through the annular member 30 to pins 31 through annular member 29 30 through pins 38 to annular member 26 and from there to the annular bearing portion 25 which engages annular member 23. By suitable adjustment of nut 29 the required supporting position is secured.

In order to insure the proper location of the 35 carrier 14 when the revolving door is shifted to the central assembled position, I provide a pair of latch members 41 and 42 shown more particularly in Figs. 6 and 8. The latch members 41 and 42 are secured to the horizontally projected 40 parallel extending flanges 43 and 44 of the diametrically extending structural member 7. The latch members 41 and 42 may be adjusted with respect to the longitudinally extending flanges 43 and 44 by means of bolt members 55 which engage the flanges 43 and 44 extending through the elongated slots 41a and 42a in the latch members 41 and 42 respectively. By reason of the elongated slots 41a and 42a in the corresponding latch members, adjustment of the latch members longitudinally of the flanges 43 and 44 may be made 45 within the limits of the slots. The latch members 41 and 42 are constructed in right hand and 50 left hand forms as shown, and each have a depending wall 41b and 42b thereon as shown, for the purpose of abutting with the edge of the longitudinally extending flanges 43 and 44. Each of the latch members includes a cam shaped surface portion 41c and 42c formed adjacent a laterally extending locking groove 41d and 42d. The extreme upper surface intermediate the cam shaped surface 41c and groove 41d in the case of latch member 41, and cam shaped surface 42c and groove 42d in the case of latch member 42 is 55 flattened as indicated at 41e and 42e, respectively. The function and operation of the latch members will be clear from a consideration of the arrangement of the laterally extending locking bar 45. The laterally extending locking bar 45 is substantially U-shaped in contour and has the extreme ends thereof directed downwardly in a position in which the said ends are adapted to engage the grooves 41d and 42d in the latch members 41 and 42, respectively. The locking bar 45 is secured 60 65 70 75 80 85 90 95 98 99 100

centrally thereof by means of strip member 46 through a welded or other form of connection. The strip member 46 extends centrally of the carrier 14 and is secured to the sleeve member 47 which envelopes the rod 18 on which roller members 12 are carried.

Sleeve 47 is adapted to freely pivot about rod 18 and allow the bar 45 to be raised or lowered within the required limits. That is to say, the bar 45 automatically gravitates into a locking position with the ends thereof engaged in grooves 41d and 42d in latch members 41 and 42, respectively. The manner in which the automatic locking operation is effected will be understood when the rolling movement of the carrier 14 to central position is considered. As the carrier 14 rolls to central position, the depending ends of weighted bar 45 ride upon cam faces 41c and 42c and over the horizontal surface portions 41e and 42e and drop into the grooves 41d and 42d in which the bar 45 remains locked. The revolving door is, therefore, centered in the correct position within the drum. When it is desired to collapse the door and shift the door wings in collapsed position to one side of the drum, a suitable tool, rod or stick is inserted upwardly through the hollow central shaft to a position beneath the strip 46, and the strip elevated a sufficient amount to raise the ends of bar 45 from engagement with the grooves 41d and 42d, thereby allowing the carrier 14 to be rolled to one side of the drum. Upon returning the carrier to central position the operation of locking the carrier in central position is wholly automatic as has been heretofore explained.

In order to insure the carrier against movement beyond central position I provide a laterally extending brace member 48 which is bolted to opposite walls of the member 1 by suitable means indicated at 49 and through which the central screw 50 extends. The central screw 50 is adjusted by gripping the head 51 thereof and when projected the selected distance to form an abutment or stop for the end 16 of carrier 14 a lock nut 52 is tightened against the brace member 48, thereby insuring the rigid maintenance of the stop in position. A precision adjustment may be made so that the carrier is prevented from movement toward the right as viewed in Fig. 1 beyond a position where rotary shaft 4 almost contacts with the ends of the slots 8 and 9 leaving sufficient clearance to insure proper rotation of the revolving door.

Once the adjustments which I have explained have been made for the trolley and the supporting mechanism for the revolving door associated with the trolley, and the latch members properly located in position, it is unnecessary to give further attention to the mechanical assembly of the trolley as the equipment functions indefinitely with substantially no attention. As hereinbefore pointed out, the journaling of the revolving door may be facilitated by employing a suitable ball bearing race as part of the thrust bearing structure in lieu of the type of thrust bearing illustrated.

The form of my invention shown in the drawings has been found to be very practical in its construction, assembly and operation, but I desire that it be understood that I intend no limitations upon my invention and that modifications and rearrangement of parts may be made within the scope of the appended claims without departing from the spirit of my invention.

What I claim as new and desire to secure by Letters Patent of the United States is as follows:

1. A trolley for revolving doors comprising a rail system, a carrier movable on said rail system from a position adjacent one side of a revolving door drum to a position centrally of the drum, latching devices on said rail system on either side of the center of the drum, and means on said carrier for gravitationally engaging said latching means for maintaining said trolley centrally of the revolving door drum.

2. A trolley for revolving doors comprising a rail system, a carrier engaging said rail system and providing mounting means for a revolving door shiftable from a collapsed position of the door to an assembled position of the door, latching means carried by said rail system on either side of the assembled position of the door, and a gravitationally operated inverted U-shaped locking bar mounted on said carrier and engageable with said latching means when said trolley is moved to the assembled position of the door.

3. A trolley for revolving doors comprising, in combination with a rail system, a carrier on said rail system movable to a position adjacent one side of the revolving door drum and to a position centrally of the revolving door drum, latching means carried by said rail system on either side of the center of the drum, and a gravitationally operated locking bar pivotally mounted with respect to said carrier and engageable with said latching means for maintaining said carrier in a central position with respect to the drum of the revolving door.

4. A trolley for revolving doors comprising a rail system extending diagonally of the drum of the revolving door, a carrier mounted on roller members engaging said rail system and movable from a central position to a position adjacent one side of the drum of the revolving door, latching means comprising latching members carried by said rail system on opposite sides of the center of the drum of the revolving door, and an inverted U-shaped bar member mounted centrally over the revolving door, the ends of said inverted U-shaped member engaging said latching members when said carrier is moved to a position centrally of the door drum and being disengageable with respect to the latching members when the carrier is moved to a position remote from the center of the drum of the revolving door.

5. A trolley for revolving doors comprising a rail system extending diagonally of the drum of a revolving door, a carrier, rod members extending through the carrier, rollers carried by said rod members and engageable with said rail system, latch members carried by said rail system, a weighted bar, means pivotally mounted with respect to one of said rod members on the carrier for supporting the weighted bar, said weighted bar being engageable with said latch members when said carrier is moved to a position centrally of the revolving door drum and being disengageable with respect to said latch members when said carrier is shifted to a position remote from the center of the revolving door drum.

6. A trolley for revolving doors comprising a rail system extending diagonally of the drum of the revolving door, a carrier, rod members extending through the carrier, rollers carried by said rod members and engageable with said rail system, latch members adjustably supported on said rail system, a weighted bar gravitationally engageable with said latch members, means pivotally mounted with respect to one of said rod members for sup-

- porting said weighted bar, said means being shiftable to allow engagement or disengagement of said weighted bar with said latch members.
7. In a revolving door, a rail system, a carrier supported by said rail system and shiftable from a position centrally of the drum of the revolving door to a position adjacent one side thereof, latching means for said carrier in the central position, and an adjustable stop supported by said rail system for providing a limiting abutment for said carrier independent of said latching means when said carrier is moved to a position centrally of the revolving door drum.
8. In a revolving door, a trolley structure including a guide rail, said guide rail being formed from metallic sheet material having a longitudinally extending central portion, a pair of horizontally disposed parallel extending shoulder portions and a pair of horizontally disposed parallel extending flange portions, and a carrier having roller members engageable with said shoulder portions.
9. In a revolving door, a trolley structure including a guide rail, said guide rail being formed from metallic sheet material having a longitudinally extending central portion, a pair of horizontally disposed parallel extending shoulder portions and a pair of horizontally disposed parallel extending flange portions, a carrier having roller members engageable with said shoulder portions, and latching means engageable with said flange portions for maintaining said carrier in a position centrally of the revolving door drum.
10. In a revolving door, a trolley structure including a guide rail, said guide rail being formed from metallic sheet material having a longitudinally extending central portion, a pair of horizontally disposed parallel extending shoulder portions and a pair of horizontally disposed parallel extending flange portions, a carrier having roller members engageable with said shoulder portions, latching means engageable with said flange portions for maintaining said carrier in a position centrally of the revolving door drum, a bridging member extending between the side walls of said guide rail, and a screw device extending through said bridging member and adjustably secured therein for forming a limiting abutment for movement of said carrier.
11. In a revolving door trolley, a rail system, a carrier, sets of rollers for supporting said carrier with respect to said rail system, and means pivotally mounted about one of said sets of rollers for locking said carrier in a predetermined position with respect to said rail system.
12. In a revolving door trolley, a carrier, an inner and an outer vertically disposed cylindrical member mounted on said carrier and spaced apart, an annular bearing therebetween, a revolving door shaft extending vertically through the inner cylindrical member, a trio of ring members pivotally mounted with respect to each other on horizontal axes normal one to the other, means connecting the inner one of said ring members with said shaft, and means for supporting the outer one of said ring members with respect to said annular bearing.
13. In a revolving door trolley, a rail system, a carrier, a member extending laterally through each end of said carrier, roller members supported by each of said members, a sleeve concentrically disposed about one of said members, an arm supported by said sleeve, a weighted yoke carried by said arm, and means for gravitationally locking the ends of said weighted yoke with respect to said rail system for locating said carrier in a predetermined position with respect to said rail system.
14. In a revolving door trolley, a rail system, a carrier, a member extending laterally through each end of said carrier, roller members supported by each of said members, a sleeve concentrically disposed about one of said members, an arm supported by said sleeve, a weighted yoke carried by said arm, and cam faced latch members carried by said rail system and gravitationally engageable with the ends of said weighted yoke for maintaining said carrier in a predetermined position.
15. In a revolving door trolley, a rail system, a carrier, a member extending laterally through each end of said carrier, roller members supported by each of said members, a sleeve concentrically disposed about one of said members, an arm supported by said sleeve, a weighted yoke carried by said arm, and cam faced latch members adjustably mounted on said rail system and coacting with the depending ends of said weighted yoke for gravitationally locking said carrier in a predetermined position.
16. In a revolving door trolley, a rail system, a carrier supported on said rail system and disposed in fixed relation to the floor, an anti-friction rotatable bearing supported by said carrier, means for mounting a revolving door shaft between said carrier and the floor with an end thereof projecting concentrically within said bearing, and a trio of ring members pivoted with respect to each other on axes normal one to the other, one of said ring members supporting said shaft and another of said ring members mounted with respect to said bearing.
17. In a revolving door trolley, a rail system, a carrier supported on said rail system and disposed in fixed relation to the floor, a pair of concentrically disposed cylindrical members mounted on said carrier and providing an annular journal therebetween, an anti-friction rotatable bearing mounted in said journal, means for mounting a revolving door shaft between said carrier and the floor with an end thereof projecting concentrically within said cylindrical members, and a pair of ring members disposed between said bearing and said shaft, said ring members being pivoted on axes normal to each other for compensating for differences in the angular position of the revolving door shaft.
18. In a revolving door trolley, a carrier disposed in fixed relation to the floor, and means for mounting the shaft of a revolving door between said carrier and the floor, said means including an anti-friction bearing mounted on said carrier and means disposed between said bearing and said shaft for accommodating inaccuracies in the vertical alignment of said shaft.
19. Mounting means for a demountable shaft comprising a fixed bearing and a movable carrier, means for locating said carrier in fixed relation to said fixed bearing, and means for supporting a shaft between said carrier and said fixed bearing including an anti-friction bearing mounted on said carrier and means disposed between said anti-friction bearing and said shaft for accommodating inaccuracies in the alignment of said fixed and said anti-friction bearings.

THURLOE M. HAGENBOOK.
